SKI BINDING

**Josef Hanser, Weiler, Allgau, Germany, assignor
to Eugen Hanser, New York, N. Y.**

**Application January 28, 1938, Serial No. 187,423
In Germany February 11, 1937**

5 Claims. (Cl. 280—11.35)

This invention relates to skis, and more particularly to an improved fastening means for holding the toe of a shoe on a ski.

In devices at present available for holding the toe of a shoe on a ski, the devices in many instances are of a complicated nature making the manufacture thereof relatively expensive and rendering such devices impractical for this reason. In addition a number of the devices at 5 present available for this purpose are so constructed that adjustment thereof is limited, and such adjustment as is possible in such devices is of a coarse nature. It is, therefore, an object of this invention to provide a device of this kind 15 which is very simple in construction so that when once adjusted it will not get out of adjustment readily.

Another object of this invention is to provide a toe piece for a ski which is simple in construction and at the same time so constructed that any desired adjustment thereof may be made, and such adjustment will be maintained at all times even though certain portions or parts of the device become loosened due to expansion 25 and contraction of the wood forming the ski.

A further object of this invention is to provide an adjustable toe piece for a ski which admits of the separate adjustment of each side thereof, and wherein the adjustment of the side pieces 30 may be made at any time without injury to the surface of the ski and without affecting the character of any subsequent adjustment which may be desirable.

With the foregoing and other objects in view, 35 the invention will be more fully described hereinafter, and will be more particularly pointed out in the claims appended hereto.

In the drawing, wherein like symbols refer to like or corresponding parts throughout the several views:

Figure 1 is a detail side elevation, partly broken away and in section, of a toe piece constructed according to an embodiment of this invention.

Figure 2 is an enlarged fragmentary sectional view taken substantially on the line 2—2 of Fig. 3.

Figure 3 is a detail top plan of a pair of toe pieces constructed according to an embodiment of this invention mounted on a ski, the ski being shown in fragmentary form.

Figure 4 is a partial side view of the bracket showing the invention applied thereto.

Figure 5 is a section on line 5—5 of Fig. 4.

Figure 6 is a partial view of the bracket showing one form of fastening device, and

Figure 7 is a similar view showing another form.

Referring to the drawing, the numeral 10 designates generally a ski which may be constructed of any suitable material such as laminated wood or the like. A toe piece comprising two members 11 and 12 is secured to the upper surface of the ski 10 at a suitable point along the length thereof.

The toe piece member 11 comprises a bottom plate 13 which is provided with an upstanding flange 14 at its outer edge which has horizontal and substantial vertical slots 15 and 16, respectively, therein through which straps or like fastening means are adapted to engage. Instead of 15 slots 16, projections of various kinds may be substituted in the known manner, for hooking on, straps, springs, etc., as shown in Figures 6 and 7. Figure 6 shows one form of projections 60 and 61 bent out of the side plates to hook on 20 the end of straps or the like, and Figure 7 shows another type of projection 63 riveted on to the side plate. The upstanding flange 14 is adapted to engage against one side of a shoe. The bottom plate 13 is provided at its forward end with 25 a downwardly extending flange 17 and at its rear edge with a similar flange 18, so that the bottom plate 13 is maintained in upwardly spaced relation to the adjacent face of the ski 10.

A pair of locking or holding plates 19 and 30 20 are disposed in the space 21 between the under face of the bottom plate 13 and the top of the ski 10, the plate 19 being disposed with its outer end adjacent the front flange 17, and the plate 20 being disposed with its outer end 35 adjacent the rear flange 18. The confronting or inner ends of the plates 19 and 20 are preferably spaced apart, although if desired they may be disposed closely adjacent one another a distance sufficient to permit adjustment of one plate relative to the other.

The plate 19 is provided on its upper side with serrations or teeth 22 and 23, the serrations or teeth 22 being positioned across the front portion of the plate 19, and the serrations or teeth 23 being disposed across the rear portion of the plate 19. The under side of the bottom plate 13 is provided with complementary serrations or teeth 24 and 25 which are adapted to engage with the serrations or teeth 22 and 23, respectively, so as to hold the front portion of the plate 13 against lateral movement.

A screw or fastening member 26 which is provided with a head 27 engages through an elongated slot 28 provided in the forward portion 50 of the plate 19.

of the bottom plate 13, the head 27 of the screw 26 being countersunk in the slot 28 so that the upper surface of the plate 13 will be smooth. The shank of the screw 26 passes through a circular hole 29 provided in the front plate 19, so that the plate 19 may be pivotally adjusted on the ski 10, but is held against lateral and longitudinal movement thereon.

The rear plate 20 is also provided on the upper surface thereof with serrations or teeth 30 and 31 similar to the serrations or teeth 22 and 23 of the front plate 19, and in like manner the under side of the bottom plate 13 is provided with serrations or teeth 32 and 33 engageable with the serrations or teeth 30 and 31, respectively.

A rear screw or fastening member 34 engages through an elongated slot 35 provided in the bottom plate 13 and then passes through a hole 36 in the plate 20.

20 The plates 19 and 20 may be positioned in recesses provided in the ski 10, or if desired these plates 19 and 20 may be secured to the upper surface of the ski 10. Where the plates 19 and 20 are mounted in recesses provided in 25 the ski 10 they may be made relatively thick so that the flanges 17 and 18 may engage the upper surface of the ski, or if desired additional channels may be provided for the flanges 17 and 18. In Figure 1 the plates 19 and 20 rest upon the 30 upper surface of the ski, and in Figures 2 and 3 these plates are placed in recesses. In Figure 1 the depending flanges 17 and 18 have their ends flush with the surface of the ski, and in Figures 2 and 3 they enter into recesses.

35 The toe piece member 12 is constructed similar to the toe piece member 11, having an outer flange 14' and front and rear flanges 17' and 18', respectively, which extend downwardly of the bottom flange 13'. Toothed or serrated locking plates 19' and 20' engage beneath the bottom plate 13' and are secured to the ski 10 by means of screws 26' and 36', respectively, which pass through slots 28' and 35', respectively. The under side of the plate 13' is also provided with 45 serrations or teeth engaging with the serrations or teeth of the plates 19' and 20'.

The toe piece members 11 and 12 may be adjusted relative to each other and to the ski 10, by loosening the screws 26 and 36 sufficiently to 50 permit the bottom plate 13 to be moved laterally of the ski 10. By reason of the pivotal mounting of the plate 13 locking plates 19 and 20, the adjustment of the plate 13 may be effected in such a manner that the outer upstanding flange 55 14 will contact with the side of the shoe irrespectively of the configuration of the shoe, the end flanges 17 and 18 holding the plates 19 and 20 with their confronting edges in parallelism. When the angular position of the side flange 14 60 is determined, the plate 13 may be moved inwardly or outwardly of the ski to the limit provided by the length of the slots 28 and 35 which are of a length sufficient to admit of minimum and maximum adjustment of the plate 13. After 65 the plate 13 has been properly adjusted the screws 26 and 36 are tightened so that the plate 13 will be held firmly in its adjusted position with the serrations or teeth of the plate 13 engaging with the serrations or teeth of the locking plates 70 19 and 20.

75 It will be apparent from the foregoing that an exceedingly simple and practical toe piece has been provided which may be mounted on ski constructions at present in use, and that when the toe piece has been properly adjusted it will

not easily get out of adjustment, neither will any initial or subsequent adjustment of the toe piece injure or be affected by the ski, as is the case where the teeth of the clamping devices bite into the material of the ski.

5 Instead of the slots 15, clamping devices as shown in Figures 4 and 5 can be substituted, which are adjustable to various depths of the soles of the shoes. The side plate 11 are provided with recesses 65, engaged by projections 66 on a 10 guard 67 held to the side plates by a screw fastening device 68. The shoe of the user is provided with a metal plate, as is known, and this is locked by the guard 67 when the guard is in proper position.

15 It is, of course, understood that various changes and modifications may be made in the details of construction of the above specifically described embodiment of this invention without departing from the spirit thereof, such changes and modifications being limited only by the scope of the appended claims.

20 What is claimed is:

1. Adjustable toe clamps for snowshoe fastenings, comprising toe clamps having teeth at their 25 lower sides, tooth-platelets resting on the ski and having teeth at their upper sides, said platelets being positioned on the ski so as to be relatively stationary but rotatable, and which automatically participate in every swinging movement of the 30 toe clamps when being adjusted, so that all engaging teeth constantly stand parallel to one another, and means preventing said rotary movement of said toe clamps and platelets.

35 2. A toe piece for skis comprising a pair of plate members each provided with an upstanding flange on one edge thereof, each of said plate members being also provided with a pair of elongated parallel slots therethrough, a dependent flange on the forward and rear end of each plate, 40 a pair of locking plates beneath each of said plate members, and within and engaged by said flanges of the plate members, each locking plate having an opening, interengaging teeth carried by the lower side of said plate members and the 45 upper side of said locking plates, and a headed securing member engaging through each slot and through the opening of the locking plate.

50 3. A toe piece for skis comprising a pair of shoe engaging members and means for securing said members on a ski, each of said members comprising a bottom plate, an upstanding flange on one edge of said plate, a front and rear dependent flange carried by the front and rear ends, respectively, of said bottom plate, a pair of spaced 55 apart locking plates disposed between each bottom plate and the adjacent face of the ski, interengaging teeth carried on the under side of said bottom plate and the upper side of said locking plates, said upper side being adjacent the under side of the bottom plate, said bottom plate having a pair of elongated slots therethrough, each of said locking plates having a circular opening therethrough, and said securing means comprising headed fastening members engaging through 60 said slots of the bottom plates and the openings of said locking plates.

65 4. A toe piece for skis comprising pairs of locking members having openings, means swingably securing said members on a ski, teeth on the upper side of said members, a flanged plate engaging over each pair of said locking members and provided with a pair of elongated slots to admit adjustment of said flanged plate relative to said locking members, and having teeth at 70 75

their lower sides to engage the teeth on the upper side of the locking members, said securing means engaging the ski and passing through said slots in said flanged plate, and through the openings 5 of the locking members, for locking the members together and to the ski, and an upstanding side piece carried by each of said plates.

5. A binding for skis and the like comprising plates adjustably carried by the ski for in and 10 out and rotary motion, said plates having a series of adjusting elements thereon, angle guards having upstanding parts with complemental adjust-

ing elements thereon adapted to detachably mate with the first mentioned adjusting elements whereby to hold the guards at selected elevations, said guards having lower inwardly extending portions forming the lowermost portions of the 5 guards whereby the same may extend up and down to low points above the bottom edges of said plates, and fastening means for binding the guards to the plates and the adjusting elements in interlocking relation. 10
